UNITED STATES PATENT OFFICE.

JAMES CULTON, OF ODIN, ILLINOIS.

RAILROAD-TICKET.

SPECIFICATION forming part of Letters Patent No. 399,842, dated March 19, 1889.

Application filed November 22, 1887. Serial No. 255,892. (No model.)

To all whom it may concern:

Be it known that I, JAMES CULTON, a citizen of the United States, residing at Odin, in the county of Marion and State of Illinois, 5 have invented a new and useful Improvement in Railroad-Tickets, of which the following is a specification.

My invention relates to an improvement in railroad-tickets designed to be separated, so 10 as to leave with the passenger a receipt for the money, ticket, or pass tendered by him in payment for his passage, and to furnish a stub to be retained by the conductor, and containing similar information, whereby the 15 conductor will be able to keep an accurate account of money, tickets, and passage received by him from passengers, and thereby enabled to make correct reports to the railroad company.

20 In the drawings, Figure 1 is a face view of a railroad-ticket embodying my improvements. Fig. 2 is a reverse view of the same. Fig. 3 is a face view showing the ticket when separated in two parts and illustrating the manner 25 of using the same. Fig. 4 is a similar view of the reverse side of the ticket when thus separated.

A represents a ticket of suitable length and width, which may be printed on paper, card- 30 board, or other suitable material. At the upper end of the ticket is printed the name or initials of the railroad company, and, if preferred, the name of the conductor on the train for which the ticket is issued. Below this, on 35 one side of the ticket, are the words "Half," "One," and "Fare," arranged in a vertical column, *a*, and on the other side are the words "Ticket," "Pass," and "Beyond," arranged in a vertical column, *b*. Between these said 40 columns is the number of the ticket *c*, the tickets issued by the company being consecutively numbered from one up, no two tickets bearing the same number.

d and *e* are two columns giving the names 45 of the stations on the road in reverse. Below the said two columns is a portion, *B*, of the ticket which corresponds exactly with the portion *A* at the head of the ticket, and is similarly provided with the columns *a* and *b*, be- 50 tween which is a number, *c*, corresponding with the number in the portion *A*. At the

head of the ticket, below the said portion *B* of the ticket on one side of the same, are two vertical columns, *f*, giving the names of the months. On the opposite side is a vertical 55 column, *g*, giving the numbers of the trains on the road, and between the two said columns *f* and *g* is an inscription "For transportation between the last-named station in each column of the list of stations," or words of similar 60 import. Below this the line bearing the words "Good only on this date and train," and below this the words "See other side." At the lower portion of the ticket on the face thereof are horizontal columns giving the numbers 65 of the days in the month, as at *h*, and below the same is the line having the numbers of a series of years, as at *i*. On the reverse of the ticket at the upper end thereof are words addressed to the conductor, requiring him to 70 return the stub with his collections to the ticket-auditor. Below this are vertical columns *k* and *l*, giving the names of all of the stations on the road in reverse, the said columns *k* and *l* registering with the columns *d* 75 and *e* on the face of the ticket, the name of each of the stations in each of the columns *k* and *l*, being one line higher than the name of the same station in the columns *d* and *e*. Below the said columns *k* and *l* on the reverse 80 of the ticket is an inscription addressed to passengers and containing the following words: "Conductors are instructed to furnish each passenger with a receipt on this form, showing by punch mark date of issue, num- 85 ber of train, whether ticket, cash fare, or pass has been collected. When cash fare has been collected, passengers will see that the word fare, also the name of station where passage begins and ends, is punched. When properly 90 punched and presented at any ticket office of this company within thirty days from date of issue it will be good for 10 cents." Below this inscription are two lines for the name of the station at which the money is paid when 95 the stub is taken up and the date of the transaction.

The operation of my invention is as follows: Supposing that a person travels from Kensington to Kankakee on the 28th day of Octo- 100 ber, 1887, and pays his fare on the train, the conductor will collect from the passenger ten

cents in excess of the regular fare, will punch out the words "One" and "Fare" in the column *a*, will punch out the word "October" in the columns *f*, the number 28 in one of the columns *h*, and the number "1887" in the column *i*, as shown in Fig. 3. He will also punch out the words "One" and "Fare" in the column *a* of part B, and the number of his train in the column *g*. He will then divide the ticket into two parts by making a horizontal cut between the word "Kensington" and the name of the preceding station in the column *d* to the center of the space between the columns *d* and *e*, will then make a vertical cut down said space until he reaches the word "Kankakee" in the column *e*, and will then make the horizontal cut in the said column *e* between the word "Kankakee" and the preceding station in the said column, thereby separating the ticket into two parts. He retains the part A and turns in the same to the ticket-auditor at the end of the route, and returns the part B to the passenger. The face of the part B, retained by the passenger, will indicate at the tops of the columns *d* and *e* the names of the initial and terminal stations of the passenger's trip, and, inasmuch as the columns *k* and *l* have the names of the stations therein arranged one space or line higher than the same names in the face columns *d* and *e*, the bottoms of the said columns *k* and *l* will show the names of the initial and terminal stations of the passenger's trip. When the passenger reaches the end of his journey,

he presents his stub B to the ticket-agent, 35 who refunds the excess paid to the conductor over the regular fare and turns over the stub B to the ticket-auditor, who, by comparing it with the stub A given him by the conductor, can see that the two accounts agree. If the 40 passenger tenders a ticket or pass or is traveling to a point beyond the end of the road, the conductor will make a punch opposite the appropriate word in the column *b*, and if a half-fare only is collected the conductor will 45 make a punch opposite the word "Half" in the column *a*.

A railroad-ticket thus arranged will effectively prevent the conductor from defrauding the railroad company and will furnish to 50 each passenger a receipt, which he may exhibit to the conductor in lieu of the check, such as are commonly employed in evidence that he has paid his fare.

Having thus described my invention, I 55 claim—

A railroad-ticket, A, having the lists of stations *d* *e* arranged in reverse order, and having the receipt portion B, said ticket and receipt portion having the corresponding 60 numbers *c*, substantially as described.

In testimony that I claim the foregoing as my own I have hereto affixed my signature in presence of two witnesses.

JAMES CULTON.
